UNITED STATES PATENT OFFICE.

FITCH H. BEACH AND FRED S. BEACH, OF CHARLOTTE, MICHIGAN.

BUCKET.

Application filed March 19, 1924. Serial No. 700,285.

To all whom it may concern:

Be it known that we, FITCH H. BEACH and FRED S. BEACH, citizens of the United States, residing at Charlotte, in the county of Eaton and State of Michigan, have invented a new and useful Bucket, of which the following is a specification.

This invention has reference to scoops and more particularly scoops especially designed 10 for scooping gravel, beach sand or the like, and aims to improve generally the construction as illustrated in the Patent Number 1,453,540.

An important object of the invention is the 15 provision of means for operating the scoop to throw the scoop to its inactive or active position.

Another object of the invention is to provide means for restricting lateral movement 20 of the scoop and at the same time prevent the scoop from turning over when employed for digging in deep water.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawings:

Figure 1 is a side elevation of a scoop 35 constructed in accordance with the invention.

Figure 2 is a plan view thereof.

Figure 3 is a sectional view taken on line 3-3 of Figure 1.

Figure 4 is a perspective view of the 40 scoop and its operating cables.

Figure 5 is a longitudinal sectional view through the scoop.

Figure 6 is a perspective view disclosing 45 the manner of pivotally supporting the scoop within its frame.

Referring to the drawings in detail, the reference character 5 designates the side bars of the frame in which the scoop is supported, the bars being formed preferably of sheet 50 metal.

The side bars 5 are relatively wide and are provided with a plurality of spaced openings 6 that accommodate the bolts 7 which also extend through openings in the runners 55 8 so that the runners may be adjusted vertically and cause the scoop, to be hereinafter

more fully described to operate at various levels.

The runners are formed preferably of angle bars and have their ends turned upwardly as clearly shown by Figure 1 of the drawings causing the bars 5 to ride a pre-determined distance in the ground surface over which the scoop is moving and prevent the forward end of the frame from digging 65 too far into the ground surface.

Secured to the inner surfaces of the bars 5 are bracket members 9 which have offset portions 10 provided with openings to receive the bolts 11 that also pass through 70 suitable openings in the side walls 12 of the scoop, thereby providing a means for securing the scoop to the frame which will allow for free pivotal movement of the scoop 75 within its frame.

The side walls of the scoop are connected by the upper plate 13 and rear plate 14, the lower edge of the rear plate 14 acting as a digging blade to scoop up material, which is forced into the upper portion of the scoop as the scoop is drawn over the ground surface. In order that the scoop will be braced along its side walls, bars 15 are provided and bolted to the side walls of the scoop, as shown by Figures 4 and 5 of the drawings. 80

Mounted on the upper plate 13 and disposed at a point substantially intermediate its side edges, are spaced arms 16 between which the pulley 17 is mounted, which pulley receives the flexible operating member 18 90 that is shown as operating over the pulley 19 carried in the pulley frame 20 supported by the post 21 that may be positioned in the bed of the body of water in which the scoop is working, the post being positioned at a point remote from the shore so that upon movement of the flexible member 18 in one direction, the scoop and its supporting frame is moved to a position where it may be drawn towards the shore in its operation. 95

At the forward end of the frame proper are upstanding arms indicated at 22 which are held in upright positions by means of the angular bars 23. Connecting the arms is a shaft 24 on which are mounted pulleys 25 over which the flexible members 25' operate the ends of the flexible members being secured to the plates 26 of the scoop so that as the flexible members 25 are pulled, the scoop will be tilted within its frame. 100

The flexible member 18 connects with the flexible members 25' at 27, portions of the 110

members 25' passing through eyes 28 formed in the members 29 that are secured to the side bars 5 of the frame. Thus it will be seen that due to this construction, when a 5 pull is directed to the flexible member 18 in the direction of the arrow as shown by Figure 4 of the drawings, the scoop will be moved to a position as illustrated by Figure 4 of the drawings, thereby releasing any material which may be held in the scoop, and 10 at the same time cause the scoop to be moved to a position adjacent to the post 21, whereupon the scoop is in a position to again be moved to accomplish the digging result.

15 Connecting the rear ends of the bars 5 is an angle bar 30 which is formed with an opening to receive one of the links of the chain 31 that also has connection with the rear wall 14 of the scoop, to restrict movement of the bucket towards the forward end of the frame to prevent the scoop from being moved too far forward for its return to its active position by gravitation.

20 A flexible member 32 is connected to the forward end of the frame and operates over the pulley 33, which flexible member may be wound on a suitable drum not shown, for drawing the frame and its scoop to the shore to dump the contents thereof.

25 From the foregoing it will be obvious that by pulling the flexible member 32 and slackening the flexible member 18, the frame and its group may be moved in one direction and when it is desired to dump the contents of 30 the scoop, the flexible member 18 is pulled and the flexible member 32 is slackened, thereby directing a pull on the flexible members 25 moving the scoop to a position as indicated by Figure 4 of the drawings and at 35 the same time drawing the frame and scoop to its initial or loading position.

40 It might be further stated that brackets 34 are adjustably supported on the scoop and extend laterally therefrom, the lower ends 45 of the brackets extending at right angles to be engaged by the flexible members 25 when the flexible members are tightened when the scoop is moved to its discharging position, thereby causing the scoop to be elevated from 50 the rear thereof.

We claim:—

55 1. In a scoop, a supporting frame including side bars, a scooping member pivotally supported between the side bars of the frame, a flexible member having connection with the forward ends of the frame to move the frame and scoop in one direction, a flexible member having connection with the scoop and contacting with the frame to move the frame in 60 the opposite direction and simultaneously move the scoop to a discharging position.

65 2. In a scoop, a supporting frame including side members, a scooping member pivotally supported between the side member, a

pulley supported on the upper surface of 65 the scooping member, a flexible member having connection with the frame to move the frame in one direction, a flexible member having connection with the scoop, means for securing the last mentioned flexible member 70 to the frame, and said last mentioned flexible member adapted to engage the pulley to hold the scoop and frame against turning over.

75 3. In a scoop, a supporting frame including side members, a scooping member including side walls, means for pivotally connecting the forward ends of the side walls of the scooping member to the side bars of the frame to permit the scooping member 80 to swing to a discharging position, means for moving the scoop in one direction, and means having connection with the scooping member and engaging the frame for simultaneously moving the scooping member to 85 its discharging position and moving the frame in the opposite direction.

90 4. In a scoop, a frame, angle bars on the frame, and providing runners to restrict movement of the frame within the ground surface over which the frame is moving, a scooping member pivotally supported by the frame, upstanding arms disposed at the forward end of the frame, pulleys supported by the arms, said frame having eyes, 95 flexible members passing through the eyes of the frame and over the pulleys, said flexible members having connection with the scooping member, said flexible member adapted to move the scooping member to its 100 discharging position, and simultaneously move the frame in one direction, and means for moving the scoop in the opposite direction.

105 5. In a scoop, a supporting frame including side members, bracket members secured to the side bars and spaced from the side bars, a scooping member including side walls, means extending through the side walls of the scooping member and bracket members 110 for pivotally connecting the scooping member to the frame, means for moving the scoop in one direction, and means for moving the frame in the opposite direction, and simultaneously moving the scooping member to 115 a discharging position.

120 6. In a scoop, a supporting frame, a scoop pivotally supported by the frame, a pulley mounted on the upper surface of the scoop, a flexible member operating under the pulley for normally holding the scoop in an upright position, and a flexible member for moving the scoop.

125 In testimony that we claim the foregoing as our own, we have hereto affixed our signatures,

FITCH H. BEACH,
FRED S. BEACH.
